UNITED STATES PATENT OFFICE.

JAMES J. STIVERS, OF NEW YORK, N. Y.

DESIGN FOR A BANK.

50,327.

Specification for Design.

Patented Feb. 13, 1917.

Application filed August 7, 1916. Serial No. 113,670. Term of patent 7 years.

To all whom it may concern:

Be it known that I, JAMES J. STIVERS, a citizen of the United States, residing at New York, county and State of New York, have invented a certain new, original, and ornamental Design for a Bank, of which the following is a specification, reference being had to the accompanying drawing, forming part thereof.

In the drawings Figure 1 is a perspective view illustrating the design for the bank.

Copies of this patent may be obtained for five cents each, by addressing the "Commissioner of Patents, Washington, D. C."

Fig. 2 is a similar view taken from the reverse side of the bank; and
Fig. 3 is a transverse sectional view through the bank.

I claim:

The ornamental design for a bank, as shown.

JAMES J. STIVERS.
